Minneapolis, Minn., a corporation of Delaware

Application May 31, 1950, Serial No. 165,310

9 Claims. (Cl. 200—87)

1

This invention relates to safety devices in general and, more specifically, to a safety device for use in a gas heating system for preventing operation of the fuel burning means when an unsafe condition exists.

It is customary in gas heating systems to provide some sort of safety device which is responsive to the presence or absence of a pilot flame to exert a controlling function with respect to the system which will prevent the delivery of fuel to the burner of the system should the pilot burner become extinguished or the gas pressure become so low as to produce dangerous operation of the burner. In recent years, many of the devices which sense the presence or absence of a pilot flame have been thermocouples or thermopiles which generate enough electricity, when heated by a pilot flame, to sufficiently energize an electromagnet to hold a valve or switch in a position against the bias of a spring to cause the flow of fuel to the main burner. It is this type of control with which the present invention is concerned.

One of the objects of the invention is to provide an inexpensive yet reliable safety control device that is adapted to be held in its operative position by the amount of current generated by a pilot-burner heated thermocouple.

Another object of the invention is to provide a manually operated safety reset switch having a relatively few parts that are simply yet sturdily assembled.

Another object of the invention is to provide a manually reset switch which makes use of a strip of flexible material to provide the resetting of an armature against an electromagnet while holding an electrical contact out of engagement with a cooperating contact until the electromagnet has become energized and the strip has been released.

Still another object of the invention is to provide a simple mechanism for actuation by a manually operable member to first move a member into engagement with a cooperative holding means, while retaining a contact in an open circuit position, and then to release said member to permit said contact to engage the cooperative contact.

Still further objects of the invention will become apparent upon reading the following detailed description of the invention in conjunction with the accompanying drawing wherein:

Figure 1 is a plan view of the device with portions of its elements broken away and with the cover of the device removed;

2

Figure 2 is a cross-sectional view taken along the line 2—2 of Figure 1;

Figure 3 is an end view of the device with portions of the elements broken away and with the cover removed;

Figure 4 is a fragmentary view similar to Figure 2 but wherein the elements of the device are shown in the positions they would assume in the first step of placing the switch into operating position;

Figure 5 is a fragmentary view similar to that of Figure 4 wherein the elements are shown in the positions they would assume after the second step of the placing of the switch into operation; and

Figure 6 is a fragmentary view similar to Figure 2 of a modified form of the invention.

While it will be apparent that the mechanism of this device might just as readily actuate a valve as a switch, for the sake of simplicity in illustration and description, the invention is illustrated and described in the preferred embodiment and with the preferred arrangement of its elements.

25 A mounting or base plate 11 has laterally extending and transversely offset ears 12 and 13 and transversely and upwardly extending side walls 14 and 15. The ears 12 and 13 have an aperture 16 and a slot 17, respectively, to receive mounting screws or bolts for securing the device to a suitable support (not shown). The sidewall 14 has an aperture therein (not shown) which is adapted to receive a coupling unit for BX cable or other electrical conduit. The wall 15 has a large opening (see Figure 3) which is covered by a Bakelite or other suitable insulating plate 19, carrying conventional electrical connector terminals 20.

40 Suitably secured to the base 11, by means of spot welding or rivets (not shown), is a bracket member 21 having an upwardly and transversely extending arm 22, an upwardly longitudinally extending arm 23, and an upwardly and transversely extending arm 24 for purposes to be presently described. Secured to the arm 23 by means of a screw 25, is a Bakelite or other electrically insulating panel 26 having a longitudinally extending finger 27 extending through a vertical slot (not shown) in the arm 22. It will be noted that the screw 25 will prevent the finger 27 from pulling out of the slot in the arm 22 and that the arms 22 and 23 will thus hold the panel 26 in a rigid vertical or transverse position with respect to the base plate 11.

55 A generally U-shaped bracket 28, made of

brass or any other suitable non-magnetic material, is secured to the panel 26 by means of rivets 29. A lower leg 30 of the bracket 28 supports an inverted U-shaped core 31 of an electromagnet by having a bolt 32 pass through an aperture therein, through spacing washers 33 and 34, and through an opening in the base portion of the core member 31.

Encircling one of the legs of the U-shaped core member 31, is a low voltage coil of wire 55 that is adapted to be energized sufficiently by a pilot flame heated thermocouple as to hold the armature 52 against the end of the core against the bias of spring 54, but insufficient to draw the armature 52 into engagement with the ends of the core against the bias of the spring. The coil is connected by leads 55a and 55b to the two terminal connectors 20 on panel 19. The terminals 20 are connected to the thermocouple A-B by means of internal lead wires C-D.

Secured to the inner surface of the vertically extending portion of the bracket 28, by means of the rivets 29 that hold said bracket to panel 26, is one leg of an L-shaped adjustment member 35. This member's other leg extends substantially parallel with an upper leg 36 of the bracket 28. An adjusting screw 37 extends freely through a hole near the outer end of the member 35 and is screw-threaded through a threaded hole 38 in the outer end of the leg 36. It is thus seen that by adjusting the screw 37, the distance between the leg 36 and the member 35 may be varied for a purpose to be described hereinafter.

An L-shaped terminal bracket 39 is secured to panel 26 by means of rivets 40 and bent-over tines 28a of a well-known terminal connector 20. A leg 39a of the L-shaped bracket 39 extends laterally from the panel 26 in a plane spaced above the plane of the upper ends of the core 31. One end of a substantially flat or slightly bowed leaf spring 41 is secured to the leg 39a by means of a rivet 42. The leaf spring is prevented from rotating on the rivet 42 by means of detents 43 struck downwardly from the arm 39a and engaging in notches in the edges of the leaf spring 41. Substantially centrally of the leaf spring 41 is an enlarged portion 41a having a large central opening 41b therein substantially in alignment with the bolt 32 and adjustment screw 37. The other end of the leaf spring 41 has a portion 41c that is bent outwardly at a slight angle to the adjacent portion of the leaf spring. A conventional switch contact member 45 extends through a hole in the leaf spring closely adjacent to portion 41c and is held thereon by riveting the upper end thereof over the top surface of the leaf spring.

Positioned directly below contact 45, so as to be engaged thereby when the leaf spring 41 swings in that direction, is a contact 46 riveted to a horizontally extending leg of an L-shaped bracket 47. Bracket 47, which is made of rigid electrically conductive material, such as brass, is connected to the panel 26 by means of a rivet 40 and connector terminal 20 in the same manner as is bracket 39.

Secured to the under side of leaf spring 41, concentrically with the opening 41b, is a Bakelite washer 48 having diametrically opposed peripheral recesses 49 (see Figure 4) which receive clamping ears 41d extending from the enlarged portion 41a of the leaf spring and wrapped around the opposed edges of the washer 48, through the recesses 49, to securely hold

the washer 48 to the underside of the leaf spring 41. A brass sleeve 50, having an enlarged abutment member 51 intermediate its ends, has the upper portion thereof extending upwardly through the Bakelite washer 48, and a lower portion extending downwardly through a hole in an armature 52 with a forced fit so as to hold the armature 52 tightly against the lower surface of the abutment 51. A cotter pin 53 extends downwardly through the sleeve 50, with the loop portion thereof extending above the upper end of the sleeve 50 and the tines thereof extending laterally below the lower end of the sleeve 50.

15 A coil tension spring 54 has a lower hook portion which engages the loop of the cotter pin and an upper hook portion which extends through a pair of spaced holes 35a in adjustment member 35, one of which is broken away in Figure 1 of the drawing. It is thus seen that the spring 54 will lift the armature 52 away from the core 31 of the electromagnet and hold the upper surface of the abutment 51 against the under side of washer 48, and tend to lift the leaf spring 41. The tension of the spring 54 is adjusted by means of the screw 37 so as to enable such spring to hold the contact 45 out of engagement with the contact 46. With this arrangement, it is obvious that the normal bias 20 of the leaf spring 41 must not be strong in the direction of bias of spring 54 to enable adjustment of said bias. The bias of spring 41 may be in opposition to spring 54 provided spring 54 is the stronger.

25 The means for actuating the armature 52 into engagement with the electromagnet comprises a generally U-shaped bracket 56 secured to panel 26 by means of rivets 57. The legs of the bracket 56 have vertically extending slots 58 and 59 therein, respectively, which slidably receive a flat Bakelite plunger 60.

30 The plunger 60 has an upwardly extending portion 60a forming an enlarged head, a step portion forming an abutment shoulder 60b at the lowest edge thereof and an inner step portion forming an abutment shoulder 60c (Fig. 2) on the bottom edge of the inner portion of the plunger 60. A coil compression spring 61 surrounds the inner portion of the plunger 60 and bears against the inner leg of the bracket 56 and the shoulder 60c to normally urge the plunger 60 outwardly, or to the left as viewed in the figures of the drawing. The plunger is prevented from being shoved completely out of the bracket 56 by means of a transversely extending portion of the outer end of coil spring 61, which extends through a hole 66d in the plunger 60, said end of the spring bearing against the outer leg of the bracket 56 in the normal position of the plunger. The portion 60a limits the inward movement of the plunger 60 by engaging the outer surface of the U-shaped bracket member 56.

35 A cover 62 has a vertically extending slot 62a adapted to permit the head 60a of the plunger 60 to pass freely therethrough when positioned on the base plate 11. The sidewalls of the cover are also upwardly recessed from the bottom thereof, to expose the walls 14 and 15 yet come sufficiently close thereto as to prevent dust from getting into the device. The cover is held on the base 11 by means of a downwardly and outwardly extending hook portion 63 which is adapted to extend through a slot 11a in the base plate and hook under the bottom surface of the

base plate adjacent said slot. A hole (not shown) in the other end of the cover 62 enables a screw 64 to pass therethrough and screw-threadedly engage in a threaded hole (not shown) the upwardly extending member 24 on bracket 21.

Operations

With the device described above connected in a heating system, as schematically shown in Figure 1 of the drawing and with the terminal brackets 39 and 47 electrically connected to a suitable control means for a main fuel supply to the burner, the operation of the device is as follows:

After the pilot burner has been ignited by suitable means (not shown), the above described safety device is placed in operative position by shoving the plunger 60 inwardly to cause engagement of the shoulder 60b with the free end of the portion 41c of leaf spring 41. Continued movement of the plunger against the bias of spring 61 will cause the leaf spring 41 to buckle downwardly in an obvious manner to cause the elements of the device to assume the positions shown in Figure 4. That is, the armature 52 in engagement with the upper ends of the core 31 of the electromagnet, with the contact 45 still out of engagement with but closer to the contact 46 than in its normal position as shown in Figure 2. Then, if the coil 55 of the electromagnet is sufficiently energized, indicating that the flame is of sufficient intensity to cause the thermocouple to provide a sufficient amount of electricity to energize the coil the required amount, a releasing of the plunger 60 to return to its normal position under the bias of spring 61, will cause the leaf spring 41 to bias the contact 45 into engagement with contact 46. It will be noted that in this position, the free end of the portion 41c will be out of alignment with the shoulder 60b so that any subsequent pressing of the plunger 60 will not cause disengagement of the contact 45 from contact 46. The only way that these contacts would separate after the device has been placed in operation, would be by removing the cover and manually moving the contacts apart, or by breaking the circuit to the coil by disconnecting one of the leads to the thermocouple. Of course, the contacts 45 and 46 will separate if the pilot burner becomes extinguished or of such low intensity that the thermocouple will not be heated sufficiently to hold the armature 52, or, in other words, if the device goes into safety operation in the manner in which it is intended. It is thus apparent that the circuit to the controller for the main fuel supply will not be completed unless a pilot flame is present, as the inward and outward movements of the plunger 60 will merely cause the up and down movements of the armature 52 under the bias of spring 54 unless coil 55 is sufficiently energized to hold the armature 52 once it has been engaged by the core 31. This provides the so-called "safety reset" of the control device.

While the preferred embodiment of the invention has been described above, a slightly different modification of the spring arrangement, as shown in Figure 6, may be satisfactorily used. It will be noted that in this modification, the coil spring 54, member 35, and the upper leg 36 of the bracket 28 is dispensed with and that the armature 52 is secured to the insulation washer 48 with a spacing washer 71 therebetween by

means of a bolt 72 loosely fitting through said members 48, 52 and 71, with a retaining pin 72a extending through the lower end of the bolt 72. The loose fit of the armature 52 on the bolt 72 enables sufficient rocking thereof to assure a flat fit of the armature 52 on the end of the electromagnet. The leaf spring 41, on which the washer 48 is mounted as in the above described modification, is riveted to an L-shaped bracket 73 as in the modification of Figures 1-5. The bracket 73 differs from the bracket 39 in that it has a laterally extending and downwardly offset portion 73a through which an adjusting screw 74 extends. It will be observed in this modification that the normal position of the leaf spring 41 must be such that the contact 45 is normally held out of engagement with contact 46 and that the bias of the armature 52 away from the core of the magnet is provided solely by the bias of leaf spring 41. Therefore, to enable the bias to be calibrated for different dropout voltages, the adjustment screw 74 has been provided to vary the upward bias of the spring 41 on the armature 52 when it is in engagement with the electromagnet.

Except for the difference in the details of the spring arrangement, the remainder of the control device is the same as in the modification of Figures 1-5. Likewise, the resetting or the placing of the device into operating condition is identical to that of the first described modification.

As indicated above, the illustrated device is merely the preferred form of the invention. It is deemed to be obvious that the arm 41 could carry a well known bridging contact bar for two spaced contacts similar to the contact 46, instead of a single contact 45; or that the arm could have no contact means but merely be the actuating means for a well known type of plunger-operated valve which is spring biased to its closed position. In the valve arrangement, the arm 41 would be adjusted to be free of the valve plunger in the positions it assumes in Figures 1 and 4 but would engage and move the plunger to valve open position when it takes the position of Figure 5.

While it will be apparent to those skilled in the art that still other arrangements of the elements of the device and various substitutions of well-known parts for said elements may be made without departing from the spirit of the invention, it is to be expressly understood that the scope of the invention is to be determined solely from the appended claims.

I claim as my invention:

1. In a safety device, the combination comprising a flexible switch arm having a first contact on a free end thereof and fixed at its other end, a fixed second contact normally spaced from said first contact, condition responsive means normally spaced from an intermediate portion of said switch arm and operable to hold said intermediate portion when a predetermined condition exists and said intermediate portion has been moved into engagement therewith, and manually operable means normally biased away from said arm but movable to engage the free end of said arm and to exert a force substantially along the longitudinal axis thereof to flex the intermediate portion of said arm laterally into engagement with said condition responsive means and thus bias said arm so as to cause said first contact to move against said second contact when the manually operable means is released from said arm.

2. A control device comprising a control means having a first member on one end of a flexible arm which is supported at its other end, condition responsive means normally spaced from an intermediate portion of said arm and operable to hold said intermediate portion when a predetermined condition exists and said portion has been moved into engagement therewith, a second member of said control means normally spaced from said first member when said condition does not exist, said second member being held in engagement with said first member when said condition exists, and manually operable means having a V-shaped portion thereof for engaging said one end of said arm and exerting a force lengthwise of said arm to cause said intermediate portion of said arm to move into engagement with said condition responsive means while holding said first member out of engagement with said second member, said manually operable means being biased to free said arm for movement toward said second member under its own bias when it is released.

3. A control device comprising a control means having a first member near a free end of a movable arm, said free end being laterally offset from the remainder of said arm, said arm being supported at its other end, a fixed second member of said control means, said arm normally biasing said first member against said second member, resilient means biasing said arm and first member away from said second member, condition responsive means normally spaced from an intermediate portion of said arm and operable to hold said intermediate portion when a predetermined condition exists and said portion has been moved into engagement therewith, and manually operable means for engaging said one end of said arm and exerting a force thereon to cause said intermediate portion of said arm to move laterally into engagement with said condition responsive means against the bias of said resilient means while holding said first member in inoperative relationship with respect to said second member, said first member being movable under the bias of said arm to operative position with respect to said second member when said manually operable means is released at a time when said condition exists.

4. In combination, a generally arcuate strip of flexible material having one of its ends fixed and the other end thereof free, a first electrical contact means carried by the free end of said strip, a second fixed electrical contact means cooperable with said first contact means, resilient means acting on said strip and normally biasing said first and second contacts apart, an armature connected to said strip intermediate its ends, an electromagnet energizable by a current generated by a thermocouple heated by a pilot burner flame and positioned to be engaged by said armature, and manually operable means normally biased out of engagement with said strip but movable to engage the free end of said strip and to exert a force lengthwise thereof to buckle it into an arc of smaller radius than normal to overpower said resilient means and to cause said armature to engage said electromagnet while holding said first contact means spaced from said second contact means, the buckling being such that when the manually operable means is released to return to its normal position and the electromagnet is holding the armature the free end of the strip will move the first contact means into engagement with the second contact means.

5. In combination, a generally arcuate strip of flexible material having one of its ends fixed and the other end thereof free, a first electrical contact means carried by the free end of said strip, a second fixed electrical contact means cooperable with said first contact means and normally spaced therefrom, an armature connected to said strip intermediate its ends, an electromagnet energizable by a current generated by a thermocouple heated by a pilot burner flame and positioned to be engaged by said armature, means biasing said strip away from said electromagnet, and manually operable means having a notched portion normally biased out of engagement with said strip but movable on an axis generally parallel to the longitudinal axis of said strip to engage the free end of said strip and to exert a force lengthwise thereof to buckle it into an arc of smaller radius than normal to cause said armature to engage said electromagnet while holding said first contact means spaced from said second contact means, the buckling being such that when the manually operable means is released to return to its normal position and the electromagnet is holding the armature the free end of the strip will move the first contact means into engagement with the second contact means.

6. In combination, a substantially flat strip of flexible material having one of its ends fixed and the other end thereof free, said free end having a portion thereof at an angle to the remainder of said strip, a first electrical contact means carried by the free end of said strip adjacent said angle portion, a second fixed electrical contact means cooperable with said first contact means and normally spaced therefrom, an armature connected to said strip intermediate its ends, an electromagnet energizable by a current generated by a thermocouple heated by a pilot burner flame and positioned to be engaged by said armature, and manually operable means normally biased out of engagement with said strip but movable to engage the free end portion of said strip and to exert a force lengthwise thereof to buckle it into an arc to cause said armature to engage said electromagnet while holding said first contact means spaced from said second contact means, the buckling being such that when the manually operable means is released to return to its normal position and the electromagnet is holding the armature the free end of the strip will move the first contact means into engagement with the second contact means.

7. In a safety control device requiring resetting to its operating position after movement to its non-operating position, a holding means comprising a holding member and a held member biased to move away from said holding member and requiring movement to said holding member to again be held thereby after release, a control member having operative and inoperative positions, means connecting said control member and held member together for holding said control member in its operative position when the held member is held by said holding member, means for moving said control member to its inoperative position upon release of said held member from said holding member, said connecting means having portions thereof movable relative to each other for normally causing movement of said control device and held member together but permitting such relative movement

8. contact means into engagement with the second contact means.

between them that said held member may be moved to its held position while said control device moves toward but does not reach its operative position, and actuating means positioned to engage said connecting means adjacent said control member for so actuating said connecting means.

8. In a safety control device requiring resetting to its operating position after movement to its non-operating position, a holding means comprising a holding member and a held member biased to move away from said holding member and requiring movement to said holding member to again be held thereby after release, a control member having operative and inoperative positions, means flexibly connecting said control member and held member together for holding said control member in its operative position when the held member is held by said holding member and for moving said control member to its inoperative position upon release of said held member from said holding member, said connecting means normally causing movement of said control device and held member together but providing relative movement therebetween so that said held member may be moved to its held position while said control device moves only part way toward its operative position, and actuating means normally spaced from but movable into engagement with said connecting means adjacent said control device for so actuating said connecting means.

9. In a safety control device requiring resetting to its operating position after movement to its non-operating position, a holding means comprising a holding member and a held member biased to move away from said holding member and requiring movement to said holding

member to again be held thereby after release, a control member having operative and inoperative positions, flexible means connecting said control member and held member together for holding said control member in its operative position when the held member is held by said holding member and for moving said control member to its inoperative position upon release of said held member from said holding member, said flexible connecting means comprising elongated arm means having a fixed end and a free end, said control member being positioned on said flexible means near said free end, means for applying force to said free end of said arm means generally lengthwise thereof to move the ends of said arm means closer together so that an intermediate portion of said arm means is moved laterally to a greater extent than said control member, said control member being actuated by said free end and said held member being actuated by said intermediate portion whereby said held member may be moved to its held position while said control member is moved toward but not to its operative position, said free end being biased to move said control member to its operative position when said held member is held in its operative position and said force applying means is free of said arm.

ROBERT J. KUTZLER.
